MAURICE M. KASANOF, OF NEW YORK, N. Y.

FABRIC STRETCHING AND STEAMING MEANS.

Application filed November 18, 1922. Serial No. 601,779.

To all whom it may concern:

Be it known that I, MAURICE M. KASANOF, a citizen of the United States, and a resident of the city of New York, borough of the Bronx, in the county of Bronx and State of New York, have invented a new and Improved Fabric Stretching and Steaming Means, of which the following is a description.

10 My invention relates to stretching and steaming fabrics and more particularly is made applicable for tubular fabrics for the production of neckties and other articles and has in view to produce a bias fabric

15 from a nonbias fabric.

The general object of my invention is to provide a stretcher device constituting an improvement on the stretcher device forming the subject matter of an application filed by me August 22, 1922, Serial Number 583,613 as well as to provide steaming means coordinated with the stretcher so that the fabric when operated upon can be swung into position to be subjected to the action 25 of the steaming means.

The manner and means whereby the above and other objects are attained will clearly appear as the description proceeds.

Reference is to be had to the accompanying drawings forming a part of this specification, it being understood that the drawings are merely illustrative of practical examples of the invention.

Figure 1 is a plan view of stretching and steaming means embodying my invention;

Figure 2 is a side elevation thereof of a portion of the supporting frame or structure broken away;

Figure 3 is a transverse vertical section 40 indicated by the line 3—3, Figure 1;

Figure 4 is an enlarged fragmentary plan view of parts of the rear portion of the stretcher;

Figure 5 is a longitudinal vertical section 45 of the rear portion of the stretcher as indicated by the line 5—5, Figure 4;

Figure 6 is a transverse vertical section through the stretcher on the line 6—6, Figure 4;

50 Figure 7 is a transverse vertical section

through the stretcher as indicated by the line 7—7, Figure 4;

Figure 8 is an enlarged cross section through the steam boxes as indicated by the line 8—8, Figure 1;

Figure 9 is a face view of a fragment of one of the steam boxes on the scale of Figure 8;

Figure 10 is a fragmentary plan view with parts broken away and in section, showing a modification of the stretcher;

Figure 11 is a fragmentary plan view of the rear end of the stretcher, the view being given to show a modified assemblage for giving longitudinal movement to the stretcher blades.

Figure 12 is a view similar to Figure 10 but showing the expanding element in the position it is given when the blades are collapsed;

Figure 13 is a cross section on the line 13—13, Figure 10.

In carrying out my invention in practice in accordance with the illustrated example, two elongated steam boxes 15 are provided, supported on a suitable frame structure 16.

A stretcher is employed, here designated generally by the numeral 17, and corresponding substantially with the stretcher in my aforesigned application. Said stretcher, however, at its rear end has in the present form, a depending pivot pin 18 adapted to turn in a fitting 19 constituting a bearing, said fitting being associated with a member 116 of the frame 16. A support for the forward end of the pivoted stretcher 17 is provided in the form of an arcuate rest 20 on supports 120, said rest having a sleeve 21 formed with flanges 22. The stretcher 17 is adapted to rest on said sleeve 21 so that the sleeve and stretcher may move on the rest 20 between stop collars 23 and 123 for arresting the stretcher in a position between the steam boxes 15 or in a position away from the steam boxes. The steam boxes 15 are supplied from a steam pipe 24 which is a part of the supporting structure 16, said steam pipe having branches 124 terminating in nozzles or outlets 25 that enter the steam boxes 15. The steam boxes have jet nozzles

26 extending within the boxes to approximately the center so as to discharge dry steam instead of taking steam from adjacent the walls where greater condensation takes place.

As in the case of my previous stretcher referred to the stretcher 17 has spaced sides 27 through which pass pins 28, (Figure 10) which form no part of the invention claimed herein, said pins 28 being fully described as part of the stretcher claimed in my previous application referred to. Centrally between the sides 27 is adapted to be disposed an elongated flat expanding element 29. The element 29 has a suitable handle 30 at one end thereof. Alining holes 31 are provided in the sides 27 to receive pins on a clamp described in my previous application for clamping the fabric along a central line when the fabric is to be stretched at opposite sides from the center line as fully set forth in my mentioned application. As in the previous stretcher also there is provided between the sides 27 of the stretcher 17 elongated expanding blades 33, 34, the respective blades having oppositely disposed teeth along their outer edges. The stretcher is inserted in the tubular fabric to be stretched for transforming the fabric so that its transverse design elements will be disposed obliquely. A spring 35 connects to blades 33, 34 adjacent their rear ends tending to withdraw their edges within the sides 27 and as shown in Figure 1 additional elastic or spring rings 36 are in practice slipped onto the forward end of the stretcher 17 tending to move the blades 33, 34 to the inner position. The expanding element 29 has a thickened square portion 37 near the handle end to enter between thickened portions 133, 134 of blades 33, 34 to maintain the latter approximately parallel as they expand. The outward movement of the blades 33, 34 is limited by a square sleeve 38 which embraces the same at the rear end of the stretcher. For actuating blades 33, 34 I provide a lever 39 having a cross head 139 fulcrumed at the center by a bolt or pin 40 held to the sleeve 38. The cross head 139 has transverse slots 41 through which screws or pins 42 extend into the blades 33, 34. The arrangement is such that the rocking of the lever 39 on its fulcrum pin 40 will through the slot and pin connections 41, 42 move the blades 33, 34 in opposite directions as will be clear from an examination of Figure 4. In my previous application referred to means are disclosed for clamping the fabric on the stretcher along a medial line and moving the blades in the same direction to stretch the fabric from a center line at each side and for giving a bias form to the fabric. For carrying out said operation I have shown in Figure 11 the blades 33, 34 operated by two handles 239

each having a slot 141 similar to the slots 41 in Figure 4 and receiving the pins 42 of Figure 4, the pin 40 serving to fulcrum both levers. It will be obvious that moving of the levers 239 will move the blades 33, 34 in the assemblage of Figure 11, the teeth on the blades being disposed in the same direction as described in my aforesigned application.

In Figure 10 the blades 233, 234 have spaced cam projections 43 at their opposed edges adapted to be accommodated in depressions 44 in the opposed edge of the adjacent blade when the blades move toward each other. An expanding element 129 presents projections 229 at opposite sides corresponding with the projections and depressions 43, 44 of the blades 233, 234 so that as said expanding element is moved forwardly it will engage the cam projections 85 of the blades and expand said blades. The dimensions of the projections on the expanding element 129 and on the blades 233, 234 are such that the movement of the blades longitudinally relatively to each other for giving bias form to the fabric will not disturb the relation between the expanding element and the blades so that said blades will maintain their expanded positions.

The numeral 128 indicates the slot in which the screws 28 are received as in my previous invention so that the blades may move laterally relatively to each other and may move longitudinally.

Reverting to the levers 239 and their slots 141 it will be seen that the slot and pin connection between said levers and the blades 33, 34 will not prevent the spring 35 from drawing the blades toward each other whenever the expanding element 29 is withdrawn from between said blades.

The jet nozzles 26, more particularly those of the upper steam box 15, are provided in view of the fact that the stretcher is mounted to move between the two boxes and to receive steam above and below. The water of condensation which inevitably forms at the bottom of the upper box 15 would find exit through the steam orifices and wet the fabric. The wetting of the fabric would prevent the proper setting of the fabric in the stretched form. Therefore, the nozzles are an adjunct of the organism comprising the upper and lower boxes and the stretcher mounted to be moved therebetween. The lower nozzles 26 also to a lesser extent prevent the fabric from being wetted. The presence of the nozzles prevents the moisture collecting at the under side of the top of the lower box 15, from being forced outward against the fabric.

I would state in conclusion that while the illustrated examples constitute practical embodiments of my invention, I do not limit

myself strictly to the exact details herein illustrated, since, manifestly, the same can be considerably varied without departure from the spirit of the invention as defined in the appended claim.

Having thus described my invention, I claim:—

A device of the class described compris-

ing a steaming means, a pivoted fabric stretching device mounted to move to or from a position to be subjected to the action of the steaming device, and a slidably support for the stretcher distant from the pivot thereof.

MAURICE M. KASANOF.
